TREE-FELLING TOY

Donald R. Rockwood, Lancaster, Calif.

Application August 17, 1953, Serial No. 26,482

Term of patent 7 years

(Cl. D34—15)

To all whom it may concern:

Be it known that I, Donald R. Rockwood, a citizen of the United States, residing in Lancaster, in the county of Los Angeles and State of California, have invented a new, original, and ornamental Design for a Tree-Felling Toy, of which the following is a specification, reference being had to the accompanying drawing, forming part thereof.

Fig. 1 is a perspective view of a tree-felling toy, showing my new design.

Fig. 2 is an end elevational view thereof in another position.

I claim:

The ornamental design for a tree-felling toy, substantially as shown.

DONALD R. ROCKWOOD.
